AUTOMATIC APPARATUS FOR SUPPLYING STEAM AND LUBRICANT TO ENGINE CYLINDERS

Application filed August 27, 1926, Serial No. 131,970, and in Great Britain September 9, 1925.

This invention relates to improved automatic apparatus for supplying steam and lubricant to engine cylinders, particularly when they are cut off from the main supply 5 of actuating fluid, and is specially applicable to locomotives.

Certain classes of engines have to run for periods during which the supply of actuating fluid, say steam, is cut off from the cylinders, as for example in the case of locomotives when descending a long incline, or of winding engines when decelerating; and during such periods, and at each stroke, a vacuum is formed in the cylinder, under which conditions the usual lubricating devices, which perform satisfactorily so long as actuating steam is being supplied to the cylinders, fail to act efficiently; moreover, when at the ends of the respective strokes, a cylinder opens to exhaust, air or other gas is drawn into the cylinders through the exhaust passages, and in a locomotive, when the exhaust discharges into the smoke box, the gas thus introduced is highly charged with carbonaceous and 25 gritty impurities, and as a result carbon is deposited on the working surfaces, which are also liable to damage by the gritty materials introduced; and the object of the invention is to provide an automatic device by the use of which the production of a vacuum in the cylinders of a running engine, when the actuating fluid is cut off, is prevented automatically by the supply to the cylinders of low pressure steam, and by the use of which device steam-borne lubricant is also supplied to the cylinders at such times; the said supply of low pressure steam being automatically cut off as soon as the pressure in the cylinders or 40 valve casings through which they are supplied, exceeds a predetermined pressure which, whilst sufficient to ensure the cylinders being filled with steam at the maximum speeds, is inoperative to actuate the engine.

According to the invention a control valve 45 and a control piston therefor are so arranged and connected to a steam supply and to the engine cylinder or valve casings that whilst the pressure in the cylinders or casings is less than the predetermined pressure the said valve is opened automatically and supplies

auxiliary steam to the casing and cylinders, the arrangement being such that whilst the auxiliary steam is being so supplied a portion of it is utilized to convey lubricant to the valve casings and cylinders, usually 55 through the conduits by which, under normal running conditions, lubricant is supplied to the cylinders by the action of the actuating fluid, so that the auxiliary steam, when the actuating fluid is cut off, and if desired under 60 normal running conditions as well, acts as a medium conveying the lubricant to and distributing it over the working parts enclosed by the valve casings and cylinders, and thus ensures the efficient lubrication of these parts by the steam-borne lubricant when the engine is running normally and particularly when it is coasting; when the pressure in the valve casings or cylinders exceeds the predetermined 65 value its action on the control piston effects the closing of the control valve which then cuts off the auxiliary steam supply to the cylinders or valve casings thus preventing the auxiliary steam from attaining in the cylinders a pressure sufficient to actuate the 70 engine; this action also automatically cuts off the supply of auxiliary steam to the cylinders as soon as the main regulator valve of the engine is opened to admit actuating fluid to the engine cylinders for the normal running. When the supply of auxiliary steam to the cylinders is cut off, the supply of said steam to the lubricant conduits is also cut off, or the rate of supply thereof is modified, 75 or a supply of high pressure steam is substituted therefor.

The admission of auxiliary steam to an engine when coasting with main regulator valve closed has the further advantage of preventing the excess wear which in the absence of 80 such supply of steam then takes place in consequence of the absence of the cushioning effect of the steam at the ends of the strokes of the piston.

I have, in the accompanying drawings, 95 illustrated, by way of example, one mode of carrying out my invention in a manner suitable for application to a locomotive.

In the drawings;—

Fig. 1 is an elevation in medial section 100

showing a device for supplying steam and lubricant to the cylinders of a locomotive, and comprising a control valve, a control piston, a casing and the casing connections, the upper half of the valve spindle being shown in outside elevation; in this view the parts are shown in the position they occupy when the control valve is closed by reason of the pressure in the engine cylinders exceeding the predetermined pressure.

Fig. 1A is a similar fragmentary view, to a smaller scale, of a modification.

Fig. 2 is a view similar to Fig. 1, and shows the control valve open and the moving parts of the device in the position they occupy when the engine cylinders and lubrication conduits are being supplied with auxiliary steam.

Fig. 3 is a view of the general arrangement and shows the mode in which the apparatus illustrated in Figs. 1 to 2 is connected to the corresponding parts of the locomotive.

A is a main casing at one end of which is formed an inlet compartment d^1 and an outlet compartment e^1 separated by a partition wall a^1 in which is formed a seating B controlled by a valve C formed at the end of a valve spindle c^1 . When the valve C is open communication is established between the steam inlet D and the steam outlet E; the inlet compartment d^1 being cut off from the outlet compartment e^1 when the valve C is closed. The inlet D is connected to any suitable source of steam supply; in the case of a steam engine it is usually connected to the main steam pipe which supplies the engine with actuating steam, the connection being made on the boiler side of the main regulator valve which controls the said supply; in the case of a locomotive the connection is made by an auxiliary pipe d^3 leading to the steam space of the boiler the connection of the auxiliary pipe to the casing being made by means of the union d^2 and nut d^3 . The outlet E is connected to the engine cylinders, usually through the main steam pipe S leading to the valve casings of the several cylinders, the connection being made on the engine side of the main regulator valve R, the auxiliary steam delivery pipe e^5 being connected to the casing by the union e^2 and nut e^3 fitted to a union piece e^4 screwed into the casing.

F and G are passageways or conduits extending diametrically across the casing through the walls a^2 and a^3 which connect the centrally located boss a^4 to the walls of the casing; the conduits open into the bore a^5 of the boss a^4 as shown. The valve spindle c^1 extends through the bore of the boss a^4 , and is controlled by a control piston H fitting a cylindrical bore h^1 formed at the end of the casing A. The cylindrical bore is closed by an end cover J having a central inlet K in which fit a tail-piece or guide h^2 formed on the control piston, preferably integrally with

it as shown, said tail-piece having a central bore h^3 and a cross bore h^4 . The inlet K is connected by a suitable pipe h^5 , union h^1 and nut h^2 to the engine cylinders usually as in the case of the outlet E, through a connection to the main steam pipe S on the engine side of the main regulator valve, so that the space h^6 between the control piston H and the cover J is subject to the pressure within the engine cylinders through the inlet K, and passageways h^3 and h^4 .

The space h^6 between the control piston and the division wall a^3 is connected through the opening h^7 to any suitable source of comparatively uniform pressure, say the atmosphere.

The boss h^8 of the control piston is recessed, and is fitted with a spiral buffer spring h^9 , the one end of which bears on the fixed boss a^8 , and the other end of which bears against the bottom of the recess in the piston H. The end of the valve spindle which bears against the piston H is recessed as at c^2 and in the recess is fitted a spiral buffering spring c^3 , the one end of the spring bearing against the bottom of the recess c^2 in the valve spindle and the other end bearing against the bottom of the recess h^{10} in the piston, the spring c^3 thus forming a cushioning connection between the valve spindle and the control piston.

The movement of the valve spindle to the right, beyond the position shown in Fig. 1 may, if desired, be limited in any suitable manner. The springs c^3 and h^9 may be dispensed with; an arrangement in which the spring c^3 is dispensed with is shown in Fig. 1A.

a^7 is a screwed opening for manufacturing purposes, made sufficiently large to permit the withdrawal of the valve spindle through this end of the casing, and closed by the plug a^6 . c^4 is a bore or channel formed in the valve spindle for a purpose hereinafter described, and is closed by a plug c^6 , or partially closed by such plug provided with a calibrated through opening.

The inlets to the lubrication conduits F and G may be respectively connected through unions f^1 , f^2 , and g^1 , g^2 and suitable pipes f^5 and g^5 to means for supplying lubricant to the engine cylinders, which means, for example, may be respectively an oil pump f^6 , and a hydrostatic oil supply g^6 ; the outlets from the conduits F' and G' being respectively connected through unions f^3 , f^4 and g^3 and g^4 and suitable pipes f^7 and g^7 to the engine cylinders through the pipe S. It will be seen, therefore, that the conduits F, F', and G, G', are respectively interposed in the two lubrication supplies to the engine cylinders.

Two such connections are shown but of course one of these may be dispensed with; or more than two may be provided, in which one or more of them may be interposed in the

lubricant supply conduits leading to auxiliary apparatus.

The valve spindle c^1 has formed upon its circumference two pairs of grooves P^1 , P^2 and Q^1 , Q^2 ; of these, one groove of each pair, namely P^2 and Q^2 , communicate by means of radial passageways p^1 and q^1 respectively with the interior bore c^4 of the valve spindle, which bore is also provided with radial ports or passageways R extending from the bore to the circumference of the valve spindle. In the position of the valve spindle when the valve C is closed, as shown in Fig. 1, the radial passageways R are closed by the valve seating B , and in this position the groove P^1 aligns with the oil channels F , F^1 , the circumferential groove forming a circumferential channel connecting the oil channel F to the oil channel F^1 so that lubricant supplied to F , say from an oil pump, is in the ordinary way delivered through P , P^1 , and F^1 to the valve casing and cylinders of the engine; in this position of the valve the groove Q^1 in like manner connects the oil channel G to the oil channel G^1 , so that lubricant supplied to G , say from a head of oil, is delivered through G , Q^1 , G^1 to the valve casing and cylinders. When the valve C is opened, by the action of the apparatus as hereinafter described, and the parts take the position shown in Fig. 2, the groove P^2 aligns with the oil channels F , F^1 , the groove Q^2 aligns with the channels G , G^1 , and the ports R are uncovered; in this position steam passes through the seating B into the outlet compartment e^1 and then passes through the ports R into the bore c^4 of the spindle, and thence by the respective radial passageways p^1 and q^1 and grooves P^2 and Q^2 into the respective streams of lubricant, said steam passing with the lubricant through the respective channels F^1 and G^1 , to the engine.

Preferably through ports such as p^2 and q^2 may be provided in the case of the grooves P^1 and Q^1 through which should the pressure in the bore c^4 exceed that in the lubricant passageways when the valve is in the closed position shown in Fig. 1, any leakage steam or condense-water in the said bore c^4 is drained away to the lubricant channels; and in some cases through ports such as r^2 may be formed in the wall of the valve spindle, so located axially as shown, that a limited quantity of steam from the outlet chamber e^1 is supplied through the ports r^2 , p^2 and q^2 to the lubricant channels F^1 and G^1 when the valve C is closed; or the plug c^6 closing the end of the bore c^4 may be provided with an axially disposed through calibrated opening for the same purpose. In either case the steam supplied through the ports p^2 and q^2 would be at normal working pressure.

It is desirable that the maximum pressure which the auxiliary steam can exert in the

engine cylinder should be limited to a value below that which is sufficient to actuate the engine, and the predetermined pressure at which the valve C closes is selected on this basis.

The relative diameters of the pistons H and valve C are such that when the space h^5 is subjected to a pressure in excess of the predetermined pressure, and the space h^6 is subjected to atmospheric pressure or other uniform pressure, the excess force tending to move the piston to the right is sufficient to overcome the force due to the boiler pressure acting on the surface c^5 of the valve and also to overcome the pressure exerted by the spring h^9 , with the result that the valve C is closed rapidly as soon as the pressure in the engine cylinder exceeds the predetermined pressure.

In order to permit steam entering at K to exert proper pressure on the piston H , radial channels are formed between the stopper parts j^1 , and in order to ensure the inlet steam acting on the face c^5 of the valve C should the latter be in contact with the plug a^6 , ports such as a^9 or their equivalents are provided.

The action of the apparatus is as follows:—

Assuming that the inlet D is connected to the main steam pipe supplying the engine, on the boiler side of the main regulator valve; that the outlet E and inlet K are connected to the said main steam pipe on the engine side of the said regulator valve, and assuming that the latter is open, the moving parts take the position shown in Fig. 1 since the pressure of steam, entering at K , on the control piston H is sufficient to overcome the pressure on the other side of the piston and the pressure of boiler steam on the much smaller area of the face c^5 of the valve, in addition to any pressure that may be exerted by the spring h^9 . In the position of the apparatus shown in Fig. 1, the engine works under normal conditions, and the supply of lubricant through the channels F and G is ensured by the normal operation of the lubricating devices augmented by the flow of leakage steam or water through the ports p^1 and q^2 , or augmented by steam supplied to these ports through the ports r^2 or a port in the plug c^6 ; and as there is a continual flow of steam through the valve casing and cylinders at all times this lubricant is, by the said steam, efficiently distributed over the working parts enclosed by the casing and cylinders.

Assuming now that the regulator valve is closed, the steam pressure in the outlet compartment e^1 and the space h^5 between the piston H and the cover J will now fall to a value below the predetermined pressure which the apparatus is designed to provide in the engine cylinders. The steam pressure on the face c^5 of the valve C will, however, be maintained at that equal to the boiler pressure,

and since the space h^6 is open to the atmosphere through the passageway h , the pressures on opposite sides of the piston will be almost balanced so that the boiler pressure on the surface c^5 of the valve would force the moving parts into the position shown in Fig. 2 in which the valve is opened, the auxiliary supply of steam entering the cylinders through the inlet D , inlet compartment d^1 , valve seating B , outlet compartment e^1 , outlet E and connection pipe to the valve casing; at the same time steam from the compartment e^1 will pass by the radial ports R to the bore c^1 of the valve spindle and thence by the passage-ways p^1 and q^1 , channels P^2 and Q^2 , to the lubricant, mixing with the latter and passing with it through the channels F^1 and G^1 to the engine cylinders. The valve openings and the size of the connecting pipes are such as to ensure the cylinders, at maximum piston velocity, being charged with auxiliary steam so as to prevent the formation of a vacuum; and the size of the radial ports R , p^1 and q^1 is such as to ensure an adequate supply of steam to the lubricant to ensure its conveyance to and distribution over the working parts.

Should the pressure in the cylinder exceed the predetermined pressure, this pressure is at once transferred to the space h^5 and acting on the face of the control piston is sufficient to move the latter and the valve spindle, in opposition to the boiler pressure on the face c^5 of the valve, into the position shown in Fig. 1 in which the supply of auxiliary steam to the cylinders is cut off, and the supply of steam to the lubricant cut off, except that due to leakage; or where ports such as r^2 are provided a supply of steam, modified either in respect to pressure or quantity, is continued.

Should the pressure in the cylinders fall below the predetermined pressure, the valve is again opened by the action first described. Generally, the predetermined pressure is so selected and the relative diameters of the valve and the piston are so arranged that an engine coasting at usual speed with the main regulator valve closed is continuously supplied with sufficient auxiliary steam to prevent the formation of a vacuum in the cylinders and to ensure efficient lubrication under these conditions.

The springs c^3 and h^9 are, as stated, not necessary for the action of the apparatus, the spring h^9 being fitted so as to prevent shock between the piston H and the boss a^8 of the casing, and the spring c^3 being fitted to prevent shock between the piston H and the valve spindle.

The arrangement illustrated is suitable for horizontal movement of the valve spindle, but in some cases a vertical arrangement of valve spindle is adopted.

In the example illustrated the inlet com-

partment d^1 , outlet compartment e^1 and valve seating B are formed integral with the main casing.

Having now fully described the nature of my said invention, what I claim and desire to secure by Letters Patent is:—

1. In a device of the character described;— a casing; an inlet chamber attached to the casing and communicating with a steam supply which is not cut off upon the closing of the valve controlling the steam supply to the engine to which the device is fitted; an outlet chamber attached to the casing and communicating with the engine cylinder; an opening formed in the wall between these two chambers; a valve to close the said opening, the end face of the valve being exposed to the pressure in the supply chamber; a control cylinder attached to the casing and connected at one end to the engine cylinder, and at the other end to a source of pressure less than the engine supply pressure; a central boss carried by the casing and provided with a bore connecting the control cylinder to the outlet chamber; a spindle actuating the valve and fitting in the said bore; a control piston in the control cylinder which piston, when the engine pressure on it exceeds a predetermined limit makes its working stroke and acting through the said spindle closes the valve in opposition to the pressure in the supply chamber, the pressure in the supply chamber acting on the valve, causing the valve to open and the control piston to make its return stroke when the engine pressure on the control piston falls below the said limit; means controlled by the valve spindle to supply lubricant to the engine cylinder when the valve is closed, and to supply a mixture of lubricant and steam from the delivery chamber to the engine cylinder when the valve is open; substantially as described.

2. In a device of the character described;— a casing; an inlet chamber attached to the casing and communicating with a steam supply which is not cut off upon the closing of the valve controlling the steam supply to the engine to which the device is fitted; an outlet chamber attached to the casing and communicating with the engine cylinder; an opening formed in the wall between these two chambers; a valve to close the said opening, the end face of the valve being exposed to the pressure in the supply chamber; a control cylinder attached to the casing and connected at one end to the engine cylinder, and at the other end to a source of pressure less than the engine supply pressure; a central boss carried by the casing and provided with a bore connecting the control cylinder to the outlet chamber; a spindle actuating the valve and fitting in the said bore; a control piston in the control cylinder which piston, when the engine pressure on it exceeds a predetermined limit makes its working stroke and

acting through the said spindle closes the valve in opposition to the pressure in the supply chamber, the pressure in the supply chamber acting on the valve, causing the 5 valve to open and the control piston to make its return stroke when the engine pressure on the control piston falls below the said limit; a lubricant supply port in the casing; a lubricant delivery port in the casing; and 10 means controlled by the movement of the valve spindle for connecting these ports together when the valve is closed, and for connecting them together and to the delivery chamber when the valve is open; substantially 15 as described.

3. In a device of the character described, a casing; an inlet chamber attached to the casing and communicating with a steam supply which is not cut off upon the closing of 20 the valve controlling the steam supply to the engine to which the device is fitted; an outlet chamber attached to the casing and communicating with the engine cylinder; an opening formed in the wall between these 25 two chambers; a valve to close the said opening, the end face of the valve being exposed to the pressure in the supply chamber, a control cylinder attached to the casing and connected at one end to the engine cylinder, 30 and at the other end to a source of pressure less than the engine supply pressure; a central boss carried by the casing and provided with a bore connecting the control cylinder to the outlet chamber; a spindle actuating the 35 valve and fitting in the said bore; a control piston in the control cylinder which piston, when the engine pressure on it exceeds a predetermined limit makes its working 40 stroke and acting through the said spindle closes the valve in opposition to the pressure in the supply chamber, the pressure in the supply chamber acting on the valve, causing the valve to open and the control piston to make its return stroke when the engine pressure 45 on the control piston falls below the said limit; a lubricant supply port in the casing connected at one end to a supply of lubricant, and opening at the other end into the bore of the boss of the casing; 50 a lubricant delivery port opening at one end into the said bore and connected at the other end to the steam supply to the engine cylinders; a circumferential groove 55 on the valve spindle connecting the said oil ports when the valve is closed; an axially disposed chamber within the valve spindle; transverse ports in the wall of the valve spindle connecting when the valve 60 is open the oil supply and delivery ports together and to the valve spindle chamber; a transverse port in the wall of the valve spindle which, when the valve is open, connects the chamber in the valve spindle 65 to the outlet chamber of the casing, and con-

veys steam from the said casing to the oil delivery port; substantially as described.

4. In combination with the elements of 70 claim 3, a transverse port in the wall of the valve spindle connecting the circumferential groove on the valve spindle to the valve spindle chamber, and a transverse port in the wall of the valve spindle connecting the valve spindle chamber to the outlet chamber of the casing when the valve is closed; substantially 75 as described.

5. In combination with the elements of 80 claim 3, a fine-bore calibrated port connecting the chamber in the valve spindle to the casing inlet chamber when the valve is closed; substantially as described.

6. The combination with the elements of 85 claim 1, of a spiral spring interposed between the control piston and a fixed part of the casing; substantially as described.

7. The combination with the elements of 90 claim 1, of a spiral spring interposed between the valve spindle and a control piston capable of axial movement relatively to the said spindle; substantially as described.

8. The combination with the elements of 95 claim 1, of a port in the casing connecting the inner end of the control cylinder to the atmosphere; substantially as described.

9. The combination with the elements of 100 claim 1, of an opening in the outer wall of the inlet chamber of the casing in alignment with the valve spindle, and of diameter large enough to permit the withdrawal of the valve spindle therethrough, and closing means 105 therefor; substantially as described.

10. The combination with the elements of 110 claim 1, of a screw-threaded opening in the outer wall of the inlet chamber of the casing in alignment with the valve spindle and of diameter large enough to permit the withdrawal of the valve spindle therethrough; closing means therefor recessed to form an annular face to engage the face of the valve in one of its extreme positions; obliquely disposed ports to admit steam to the said recess when the valve face engages the said annular face; and a spiral spring interposed 115 between the valve spindle and a control piston movable axially relatively to the valve; substantially as described.

11. The combination with the elements of 120 claim 3, of a second set of lubricant supply and delivery ports in the casing; a second groove on the spindle aligning with the said second set of lubricant ports when the valve is closed; and a second set of annular ports in the wall of the spindle aligning with the said second set of lubricant ports when the valve is open; substantially as described.

12. In a device as claimed in claim 1, a 125 control spindle capable of axial movement independently of the valve spindle; an opening at the centre of the end of the control chamber communicating with the engine 130

cylinder; a tail-piece connected to the control piston and guided in the said opening; and longitudinal and transverse ports in the said tail-piece; substantially as described.

- 6 13. In a device as claimed in claim 1 in which the inlet chamber is connected to the engine steam supply on the boiler side of the valve which controls the said supply to the engine; substantially as described.
- 10 14. A device as claimed in claim 1, a casing having the inlet chamber located at one end thereof, the supply chamber being located adjacently thereto, and divided therefrom by a wall, in which the opening closed
15 by the valve is located, a control cylinder being located at the other end of the casing coaxially with the said opening, the boss in which the bore of the valve spindle works being located at the centre of the casing, and
20 being carried from the casing by connecting parts through which the oil supply and oil delivery ports pass; substantially as described.

In testimony whereof I set my hand.
